[57] CLAIM

The ornamental design for a mobile antenna transport trailer, substantially as shown and described.

DESCRIPTION

FIG. 1 is a side elevational view of a mobile antenna transport trailer showing my new design; it being understood that the broken line showing of the antenna is for illustrative purposes only;

FIG. 2 is a top plan view;

FIG. 3 is a bottom plan view;

FIG. 4 is a front elevational view; and

FIG. 5 is a rear elevational view.
